US0D1017009S

(12) **United States Design Patent** (10) Patent No.: **US D1,017,009 S**
(45) Date of Patent: ** Mar. 5, 2024

(54) **STOVE**

(71) Applicant: **Huizhou Haorui Hardware Technology Co., Ltd**, Huizhou (CN)
(72) Inventors: **Yong Zhang**, Huizhou (CN); **Chaosen Wang**, Huizhou (CN)

(**) Term: **15 Years**

(21) Appl. No.: **35/515,877**

(22) Filed: **Dec. 9, 2022**

(80) **Hague Agreement Data**

Int. Filing Date: **Dec. 9, 2022**

Int. Reg. No.: **DM/225677**

Int. Reg. Date: **Dec. 9, 2022**

Int. Reg. Pub. Date: **Dec. 30, 2022**

(51) LOC (14) Cl. **23-03**

(52) U.S. Cl.

USPC **D23/343**

(58) **Field of Classification Search**
